(57) **CLAIM**

I claim the ornamental design for a pendant or table lamp, as shown and described.

DESCRIPTION

FIG. 1 is a top, front, and left side perspective view of a pendant or table lamp showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a top, front, and left side exploded perspective view thereof.
